FIG. 3

FIG. 2

Joseph C. Coulombe ^{INVENTOR.}

UNITED STATES PATENT OFFICE.

JOSEPH C. COULOMBE, OF KOKOMO, INDIANA.

VACUUM TANK.

Application filed February 26, 1927. Serial No. 171,216.

The invention relates to a vacuum tank for feeding fuel to the carburetter of an internal combustion engine, of the type shown in my Patent No. 1,467,633, issued Sept. 11, 1923.

5 The object of this invention is to provide an efficient device economical to manufacture.

Another object of this invention is to provide means for easily and quickly priming the vacuum tank.

10 In the drawings forming a part of this application:

Figure 1 is an elevation, partly sectional, of the device.

Figure 2 is an elevation, partly sectional, 15 of the operating chamber and mechanism.

Figure 3 is a top view of the device.

An outer container 1 has a fuel outlet 2 leading to a carburetter (not shown) and a drain valve 3 in its bottom portion, its upper

20 end is open to atmosphere and has a loosely fitting dust cap 4 overlapping its upper edges to keep out foreign matter. An operating

chamber 5 is suspended within the container 1 so that its top 6 lies below the upper edges 25 of container 1 and the bottom plate 7 is above the bottom of container 1. The sides, or cylindrical portion, of chamber 5 fitting freely

within the container 1 so that it may be readily withdrawn from the container. A suction

30 fitting 8 and a fuel fitting 9 are screwed to the top 6 of chamber 5, said fittings having flange portions 10 which are adapted to rest

on the dust cap 4, said dust cap having clearance holes for said fittings. The dust cap 4

35 has an opening 11 sufficiently large to allow for quickly priming the lower container. A

cover 12 is provided with a lip 13 to conveniently allow the swinging of the cover 12 about the rivet 14 to expose the priming opening 11.

40 Fuel poured through the opening 11 finds its way to lower container by flowing over the top 6 and down along the sides between chamber 5 and the container sides.

The plate 7 is removable from chamber 5

45 and has mounted upon it the float 15 and lever mechanism 16 to operate the dump valve

17. The float 18 operates the atmosphere valve 19. The float 15 is not large enough to

50 open the valve 17 against atmospheric pressure and does not open the valve 17 until after the atmosphere valve 19 is opened by the float 18.

The buoyancy point of float 18 is at a higher level than that of float 15, so that it

will close valve 19 before the valve 17 is closed by the float 15. After valve 19 is closed, air must be admitted through the dump valve 17 during the remainder of the dumping cycle, and, in order to hasten the remainder of this dumping action, the air tube 20 is provided. The float 15 is so proportioned to the weight of valve 17 that the valve 17 will be open when the float 15 is immersed and there is no suction in the chamber 5, but will close the valve 17 when there is no liquid in chamber 5.

65 The operation of chamber 5 is as follows:

With the valve mechanism in the position shown in the drawing and the connections properly connected to an engine, fuel will flow into chamber 5 until the atmosphere valve 19 is opened by float 18, when the valve 17 will be opened by the float 15 and allow the fuel to flow by gravity into the container 70 1. When the fuel level recedes below the buoyancy point of float 18, the valve 19 will close and thereafter air will be admitted to chamber 5 by the open valve 17 and tube 20 until the fuel level recedes below the buoyancy point of float 15, when the valve 17 will close and the operation is repeated. 75

I claim:

1. In a vacuum fuel feeding system, the combination of an outer container having an open top, a loose fitting dust cap for the open top of said container, an operating chamber within said container and located below said dust cap so as to form a pocket between the top of said operating chamber and said dust cap.

2. In a vacuum fuel feeding system, the combination of an outer container having an open top, a loose fitting dust cap for the open top of said container, an operating chamber within said container and located below said dust cap so as to form a pocket between the top of said operating chamber and said dust cap, and an opening in said dust cap to allow priming said container.

3. In a vacuum fuel feeding system, the combination of an outer container having an open top, a loose fitting dust cap for the open top of said container, an operating chamber within said container and located below said dust cap so as to form a pocket between the top of said operating chamber and said dust cap, an opening in said dust cap to enable

priming said container, and a cover for said opening secured to said dust cap.

4. In a vacuum fuel feeding system, the combination of an outer container having an open top, a loose fitting dust cap for the open top of said container, an operating chamber within said container and located below said

dust cap, one or more fittings secured to said operating chamber and extending through said dust cap, shoulders on said fittings adapted to rest on said dust cap and suspend the said operating chamber within the said container. 10

JOSEPH C. COULOMBE.
